Inventor: Martin L. Smith

By Thomas G. Orwig, Attorney.

UNITED STATES PATENT OFFICE.

MARTIN L. SMITH, OF ELWELL, IOWA.

FOLDABLE TABLE-SPREAD SUPPORT.

SPECIFICATION forming part of Letters Patent No. 694,438, dated March 4, 1902.

Application filed November 18, 1901. Serial No. 82,646. (No model.)

To all whom it may concern:

Be it known that I, MARTIN L. SMITH, a citizen of the United States, residing at Elwell, in the county of Story and State of Iowa, have 5 invented a new and useful Foldable Table-Spread Support, of which the following is a specification.

My object is to provide a neat, strong, and durable support for a cloth spread over a table to conceal and protect food from insects and dust whenever desired without removing the dishes and in such a manner that the flexible material used as a spread and cover will not sag and contact with food to become 15 soiled therewith.

My invention consists in the construction, arrangement, and combination of parts in such a manner that the complete device can be readily folded when not in use and also 20 readily opened to be placed on a table and adjusted relative to dishes thereon, as hereinafter set forth.

In the accompanying drawing, Figure 1 shows the form of the main part of the device with which the adjustable parts are pivotally connected. Fig. 2 shows the device 25 opened and extended as required to rest upon a table or other flat surface for supporting a flexible spread. Fig. 3 is an enlarged transverse sectional view on the line x of Fig. 1, showing the three parts pivotally connected. Fig. 4 is a vertical sectional view of the main part adapted for pivotally connecting the adjustable parts therewith.

The letter A designates a frame made of a single length of wire. A portion of it is bent 35 into a coil to produce a tube B, and an adjoining portion is bent into a helical coil to produce a flange C, and the end portion terminates in an arch D, preferably of angular shape, as shown in Figs. 1 and 4. The lower coil at the bottom of the tube B is lowered to admit the ends of the adjustable parts and to retain them pivotally connected with the 40 tube B. The wire, extending laterally from the lower coil, is bent into form of a double curve D^2 and then extended a straight length F, that preferably terminates in concentric curves H and H^2 , from which is extended 45 outward and downward a double-curved portion J, that terminates in a coil J^2 , adapted to serve as a foot when the complete device is placed on a table.

A^2 and A^3 are duplicates of the main frame 50 A, excepting that at one end they terminate

in right-angled extensions K, adapted to be passed upward into the tube B to serve as pivots.

It is obvious the size and weight of the wire from which the frames are made and their 55 lengths may vary as required to produce different sizes of spread-supports. It is also obvious that the portions consisting of the concentric curves H and H^2 may vary in shape as required to produce various forms, plain 60 and ornamental.

To adjustably connect the parts A^2 and A^3 with the part A, it is only necessary to slip their right-angled extension K into the lower 65 end of the tube B as required to be retained by the lower coil, as shown in Figs. 1 and 4.

The arched end portion of the part A is adapted for use as a finger-hold and also as a 70 loop for hanging the device on a fixed nail or hook.

Having thus described the purpose and construction of my invention and the manner of its use, its practical operation and utility will be readily understood by persons of ordinary intelligence, and what I claim as new, 75 and desire to secure by Letters Patent, is—

1. A flexible support for a cloth spread over a table, comprising a main part in the form of a frame made of wire and one end portion coiled into a tube to project upward and the 80 other portion extended horizontally and downward and a plurality of mating wire frames that have right-angled extensions extended in the tube and pivotally connected with the said tube at the end of said main 85 part, to operate in the manner set forth for the purposes stated.

2. A foldable and adjustable support for a flexible spread on a table consisting of a main part made of wire and a portion of the wire 90 coiled to produce a tube projecting upward a convolute coil or flange at the top of the tube and terminating in a loop or arch, a double curve at the lower end of said tube and then a straight length that terminates in an 95 outward and downward ornamental extension and a plurality of mating wire frames having right-angled projections at their top ends extended into the tube at the end of the main part, arranged and combined in the 100 manner set forth for the purposes stated.

MARTIN L. SMITH.
